US0D1090478S

(12) **United States Design Patent** (10) **Patent No.:** **US D1,090,478 S**
(45) **Date of Patent:** **** Aug. 26, 2025**

(54) **RECORD PLAYER**

(71) Applicant: **SONOS, INC.**, Goleta, CA (US)

(72) Inventors: **Philippe Vossel**, Wuppertal (DE);
Edward Mitchell, Thousand Oaks, CA
(US)

(73) Assignee: **SONOS, INC.**, Goleta, CA (US)

(**) Term: **15 Years**

(21) Appl. No.: **29/975,861**

(22) Filed: **Dec. 2, 2024**

Related U.S. Application Data

(63) Continuation of application No. 29/866,867, filed on Sep. 29, 2022, now Pat. No. Des. 1,058,531.

(57) **CLAIM**

The ornamental design for a record player as shown and described.

DESCRIPTION

FIG. 1 is a first perspective view of a record player.

FIG. 2 is second perspective view thereof.

FIG. 3 is a front elevation view thereof.

FIG. 4 is a rear elevation view thereof.

FIG. 5 is a left side view thereof.

FIG. 6 is a right side view thereof.

FIG. 7 is a top plan view thereof; and,

FIG. 8 is a bottom plan view thereof.

The broken lines depict portions of the record player which form no part of the claimed design.

1 Claim, 6 Drawing Sheets
